UNITED STATES PATENT OFFICE

108,635

DESIGN FOR A TEXTILE FABRIC

Lucien Biva, New York, N. Y., assignor to William E. Roschen, Spring Lake, N. J., Albert A. Levy, New York, N. Y., and John Hastedt, Jersey City, N. J., co-executors of the Estate of Otto Timme, deceased, doing business as E. F. Timme & Son, New York, N. Y.

Application January 31, 1938, Serial No. 74,757

Term of patent 7 years

To all whom it may concern:

Be it known that I, Lucien Biva, a citizen of the United States and a resident of the Borough of Queens, county of Queens, city and State of New York, have invented the new, original, and ornamental Design for a Textile Fabric, of which the following is a specification, reference being had to the accompanying drawing, forming part thereof.

The figure is a plan view of the fabric, showing my new design.

I claim:

The ornamental design for a textile fabric, as shown.

LUCIEN BIVA.
